UNITED STATES PATENT OFFICE.

CHARLES K. SHERWOOD, OF BROOKLYN, NEW YORK.

DESIGN FOR A BOTTLE.

SPECIFICATION forming part of Design No. 25,048, dated January 14, 1896.

Application filed November 7, 1895. Serial No. 568,234. Term of patent 7 years.

To all whom it may concern:

Be it known that I, CHARLES K. SHERWOOD, a citizen of the United States, residing at Brooklyn, in the county of Kings and State of New York, have invented and produced a new and original Design for Bottles, of which the following is a specification, reference being had to the accompanying drawings, showing a part thereof.

Figure 1 is a perspective view of a bottle, showing my design, the view being taken looking slightly upward so as to show the bottle-bottom. Fig. 2 is a perspective view looking slightly downward. Fig. 3 is a bottom view of the bottle; and Fig. 4 is a top view thereof, these four figures being deemed necessary to fully illustrate my design.

The leading features of my design consist in the raised circular bottom, the outlines of which when viewed in end elevation fall within the side lines of the bottle, the rounded bottom portion curving upward from the base and merging in the side lines of the bottle,

the flattened corners, the convex top and columnar neck rising straight from the top portion of the bottle. 25

The bottle has a raised base or pedestal, which when the bottle is viewed in end elevation falls within the side lines of the bottle, and above this base is the convex bottom, which merges in the sides of the bottle and in the flattened corners, as shown best in Figs. 1 and 3. 30

The bottle has a convex top and a straight columnar neck, which rises from the middle 35 of the top portion, and the lines of the neck when viewed in end elevation fall well within the side lines of the bottle, as shown in Fig. 4.

What I claim is—

The design for a bottle herein shown and described. 40

CHARLES K. SHERWOOD.
